DAMPER REGULATOR

James R. O'Rourke, Galveston, Tex., assignor of
one-third to R. E. Fristoe and one-third to
H. F. Johnson, both of Galveston, Tex.

Application April 13, 1937, Serial No. 136,662

12 Claims. (Cl. 193—32)

The present invention relates to improvements in damper regulators, and more particularly refers to a damper regulator for controlling automatically the flow of free flowing granular materials in a spout. The invention is particularly applicable to the control of grain passing through spouts from an elevator to a conveyor.

Another object of the invention is to provide an improved damper regulator for spouts and the like in which the advantages of choke feed are improved and whereby the quantity of grain or other material that can be loaded from a spout onto a belt conveyor within a given time is materially increased.

15 A further object of the invention resides in providing an improved draft regulator which substantially eliminates dust at the point where the grain or other material is loaded onto the conveyor.

20 A still further object of the invention is to provide an improved draft regulator which will eliminate wear in the spout and require the grain to travel slowly and in contact with substantially all surfaces of the spout.

25 With the foregoing and other objects in view, the invention will be more fully described hereinafter and will be more particularly pointed out in the claims appended hereto.

In the drawings, wherein like symbols refer to like or corresponding parts throughout the several views,

Figure 1 is a vertical fragmentary section taken through parts of the grain elevator showing the spout thereof with the improved damper and its regulator applied thereto.

Figure 2 is a horizontal section taken on the line 2—2 in Figure 1 and with parts broken away.

Figure 3 is a fragmentary side view of a portion of the spout with parts broken away and parts shown in section and with the improved regulator shown in side view.

Figure 4 is an enlarged longitudinal section taken through the regulator cylinder.

Figure 5 is a transverse section taken on the line 5—5 in Figure 4.

Figure 6 is a fragmentary vertical section taken on the line 6—6 in Figure 2.

Figure 7 is a fragmentary horizontal section taken on the line 7—7 in Figure 6.

50 Figure 8 is a vertical transverse section taken on the line 8—8 in Figure 3, and

Figure 9 is a longitudinal section on a somewhat reduced scale over that shown in Figure 4 of the regulator cylinder showing the supplementary by-pass.

Referring more particularly to the drawings, and to Figure 1 particularly, the improved device is shown in connection with a system of grain handling equipment in a grain elevator. Such elevator consists generally of the hopper or bin 10 at the bottom of which there is the valve 11. Below the valve 11 is the spout 12, the upper end of which is enlarged to form a hopper 13. The spout 12 may be of any size, shape or construction of closed spout for conducting grain or other material. At the lower end of the spout 12 is a loading hopper 14 for loading the grain or other material onto a belt or other conveyor 15.

In the spout 12 at a point just above the loading hopper 14 is a sliding gate 16 having a hand piece 17 for hand operation. This gate is shown more particularly in Figures 2, 6 and 7.

The gate can be maintained in any desired position from fully closed to wide open by the keepers 18. In the spout 12 just above this gate 16 is a damper 19 suspended in the top of the spout from a shaft 20 more particularly shown in Figures 2, 3 and 8. The damper is affixed to the shaft in any appropriate manner whereby the turning of the shaft will cause the damper 25 to assume any desired angular position in the spout between an entirely closed position and a wide open position.

The purpose of the invention is to automatically control the position of the damper 19 in 30 the spout 12 and thereby regulate the flow of grain or other material between the bin 10 and the belt conveyor 15. The purpose of the damper 19 is to cause the grain or other material in the spout 12 to be held under a choke feed, that is, 35 to be held back so that there will always be a full flow of grain or other material in the spout 12 until the bin 10 is empty. When operated under choke feed, the grain or other material in the spout 12 entirely fills the spout, moves uniformly down the spout, and feeds uniformly and slowly through the loading hopper 14 onto the belt or other conveyor 15, thereby increasing the quantity of grain or other material that can be loaded from a spout onto a belt conveyor in any 45 given interval of time.

The choke feed also eliminates dust at a point where the grain or other material is loaded onto the conveyor. The choke feed also eliminates wear in the spout 12 because the grain or other material under the choke feed travels slowly and in contact with all surfaces of the spout; whereas when flowing freely without choke feed the grain or other material wears the spout away rapidly.

In order to improve the choke feed and to 55

maintain at all times a properly restricted port area at the damper to take care of all sorts of materials and of the pressure and volume in which they are fed down the hopper 12, I provide 5 a damper regulator. This regulator includes a cylinder 21, shown more particularly in Figures 4, 5 and 9, such cylinder being closed at its lower end for instance by the end cap or head 22 having a bearing 23 through which a pin 24 passes for 10 the purpose of swivelly supporting the cylinder 21 upon a bracket 25. The bracket is affixed, as shown in Figures 2 and 3, to a wall 26 of the grain elevator or to other appropriate support. The cylinder 21 is also closed at its upper end by an 15 end cap or cylinder head 27 having a stuffing box 28 therein through which reciprocates the piston rod 29. Within the cylinder 21, the rod 29 connects with a plunger or piston 30 mounted to reciprocate within the cylinder. 20 The piston rod 29 is connected at the upper end through a pin and link 31 to a lever arm 32 which is keyed to the damper shaft 20. This construction is best seen in Figures 2 and 3. Keyed to the same damper shaft 20 is a second 25 lever arm 33 on which there is adjustably positioned a counter-weight 34 whereby the weight may be set in any position along the arm 33 with reference to the shaft 20 whereby to change the leverage of the counter-weighting action. 30 A by-pass pipe 35 connects the two ends of the cylinder 21 as best seen in Figure 4. In the by-pass there is an adjustable cock 36. A second or supplemental by-pass pipe 37 connects the top of the cylinder 21 with a port 38 in the side of 35 the cylinder located an appreciable distance above the lower end of such cylinder. The by-pass 37 and port 38 are shown more particularly in Figure 9. 40 As shown more particularly in Figure 4, the piston 30 has a number of holes or passages 39 therein opening through the upper and lower faces of the piston. These holes 39 are normally covered by a disc valve 40. The disc valve 40 is slidable up and down on the piston rod 29 toward and from a closed position against the ports or holes 39. 45 The disc valve 40 is normally and yieldably urged to a closed position against the upper face of the plunger 30 by a coil spring 41, the load 50 of which may be adjusted by a set nut 42 threaded upon a threaded portion of the piston rod 29. The cylinder is filled with fluid. A reservoir or oil cup 43 contains a reserve supply of fluid and connects with the upper portion of the cylinder 55 21 by a pipe 44 by which the reservoir 43 may be supported from the cylinder. It will be understood that fluid in the cylinder 21 is gradually lost due to operation, the losses occurring around the piston rod while in operation. The cup 43 60 is provided with a ball check valve 45 acting to automatically open to replace fluid in the cylinder 21 whenever the condition of fluid therein falls below the value of the load of the spring of the ball check valve 45. 65 In operation, when there is no grain or other material flowing in the spout 12, the counter-weight 34 on the lever 33 will operate by gravity to move the damper 19 to a closed position, as shown in Figure 3. The piston 30 is at this time 70 at the bottom of the cylinder 21. When grain or other material is put into the spout 12, the weight of the grain acting against the damper 19 tends to force the damper upwardly, raising counter-weight 34 and also raising piston 30 in 75 the cylinder 21.

As the piston 30 moves up it diminishes the space in the cylinder 21 above such piston 30, which space is the upper chamber of the cylinder. Accordingly, the fluid is driven out of this upper chamber through the by-pass 35 past the cock 5 36 and into the lower chamber of the cylinder 21 below the piston 30, the upper movement of which tends to create a partial vacuum in the lower chamber to assist the propelling action in the upper chamber, both forces contributing to 10 the circulation of the fluid through the by-pass 35 to the lower chamber of the cylinder 21.

It will be understood that the cock 36 is adjustable. The rate at which fluid may pass through the by-pass 35 and permit the piston to 15 be raised and the damper to be opened is therefore controllable. Now when the piston 30 is in the lower part of the cylinder 21 the port 38 of the supplemental by-pass 37 communicates with the upper chamber of the cylinder. Therefore 20 this supplemental by-pass does not function until the piston 30 has moved the required distance upwardly to pass such port 38 and to unmask the port 38 into communication with the lower chamber of the cylinder 21. Thereupon fluid 25 begins to flow through the supplementary by-pass 37 from the upper chamber downwardly into the lower chamber. In this way the exchange of fluid from the upper to the lower chamber is accelerated and the damper 19 may open wider at 30 an accelerated speed. The cock 36 will be adjusted experimentally so that the spout 12 will be entirely filled with grain before the damper 19 is entirely open. The weight of the grain in the spout 12 will continue to hold the damper 19 open until the grain in the spout is entirely exhausted. The maximum rate of flow may be controlled by the proper setting of the slide gate 16.

When the grain in the spout 12 is exhausted, 30 it is desirable that the damper 19 close quickly in order to be in the closed position when the next draft of grain or other material is turned into the spout 12. The counter-weight 34 tends to close the damper 19 whenever pressure of the grain is 35 relieved, and in so doing causes piston 30 to move downwards in the cylinder 21. To facilitate speed in the closing of the damper 19, the ports 39 are provided in the piston 30. On the downward movement of the piston 30 in the cylinder 21 the 40 pressure of the fluid in the lower chamber exerted through the ports 39 upon the under face of the disc valve 40 will exceed the load of the spring 41 and this pressure will require the opening of the disc valve which is of less diameter 45 than the cylinder 21 whereby such fluid escaping upwardly through the ports 39 may flow about the edges of the disc valve 40 and freely into the upper chamber of the cylinder 21.

Therefore the descent of the piston 30 may 40 take place rapidly without substantial interference from the fluid pressure; whereas the upper movement of the piston will require that the fluid pressure be received upon the top surface of the disc valve 40 thus adding the fluid 45 pressure to the expansive action of the spring 41 in tending to close, and maintain in a closed position, the disc valve 40 against the ports 39. While the piston 30 is descending in the cylinder 21 the fluid also passes from the lower chamber 50 upwardly through the by-pass 35. For a portion of the descending movement of the piston 30 fluid will also be forced from the lower chamber to the upper chamber through by-pass 37. When, however, the piston 30 reaches a position op- 55

posite the port 38 the by-pass 37 will, of course, cease to function in this respect.

The present device is particularly applicable to, and desirable in, a grain elevator, especially 5 in connection with the weighing of grain in hopper scales. In Figure 1 the bin 10 may be a scale hopper in which grain is weighed in car-load lots and discharged through spout 12 at frequent intervals. It is also desirable in any 10 closed spout carrying free flowing granular materials where materials are discharged at the open end of the spout for loading onto belt conveyors or for discharging to other devices.

It is obvious that various changes and modifications 15 may be made in the details of construction and design of the above specifically described embodiment of this invention without departing from the spirit thereof, such changes and modifications being restricted only by the 20 scope of the following claims:—

What is claimed is:—

1. In combination with a closed grain spout, a movable damper therein opened by the movement of the material through the spout, adjustable means 25 tending to close said damper and to hold the damper closed until the spout is substantially full of grain, and a regulator coupled to said damper for slowing and restricting the opening movement thereof.

30 2. In combination with a closed grain spout, a movable damper therein opened by the movement of the material through the spout, means tending to close said damper, an adjustable regulator coupled to the damper and regulatable to 35 permit opening of the damper only when the spout is substantially full of grain, said regulator comprising a cylinder, a piston movably mounted in the cylinder and dividing the cylinder into opposed chambers, and a by-pass connecting said 40 chambers.

3. In combination with a closed spout for granular material, a movable damper therein opened by the movement of the material through the spout, means tending to close said damper 45 until the closed spout is transversely full of grain, a regulator coupled to the damper and comprising a cylinder, a piston movably mounted in the cylinder and dividing the cylinder into opposed chambers, a by-pass connecting said chambers, 50 and means in the by-pass for regulating the flow volume therethrough.

4. In combination with a closed spout containing granular material, a movable damper therein opened by the movement of the material 55 through the spout, means tending to close said damper when the spout is not substantially full of grain, a regulator coupled to the damper and comprising a cylinder, a piston movably mounted in the cylinder and dividing the cylinder into 60 opposed chambers, a by-pass connecting said chambers, and a supplemental by-pass of shorter length than the first mentioned by-pass controlled by the position of said piston to place the second by-pass in communication with both 65 opposed chambers of the cylinder.

5. In combination with a closed spout containing granular material, a movable damper therein opened by the movement of the material through the spout, means tending to close said damper, 70 means for adjusting the closing action of said last named means to maintain the damper in closed position except when the spout is substantially full of grain, a regulator coupled to the damper and comprising a cylinder, a piston mov- 75 ably mounted in the cylinder and dividing the

cylinder into opposed chambers, a by-pass connecting said chambers, a supplemental by-pass connecting with the upper portion of the cylinder and with a point spaced appreciably above the lower end of the cylinder whereby such supplemental by-pass will only establish communication between the opposed chambers of the cylinder after the piston has traveled an initial distance upwardly in said cylinder.

6. In combination with a closed spout containing granular material, a movable damper therein opened by the movement of the material through the spout, means tending to close said damper, adjusting means for the damper closing means whereby to cause closing of the damper except when the spout is substantially full of grain, a draft regulator comprising a cylinder, a piston therein having ports therethrough, and a one way opening valve for said ports.

7. In combination with a closed spout containing granular material, a movable damper therein opened by the movement of the material through the spout, means tending to close said damper, adjustable means associated with said damper closing means adapted to be adjusted to retain 25 the damper closed until grain collects in a substantially solid mass filling the cross-section of the spout, a draft regulator comprising a cylinder, a piston therein coupled to move with said damper, said piston having ports completely 30 therethrough, a disc over the upper portion of said piston for covering said ports, spring means for holding said disc against said ports, and means for adjusting the load of said spring means.

8. In combination with a closed spout normally containing granular material, a movable damper therein opened by the movement of the material through the spout, means tending to close said damper, adjusting means for the damper closing 40 means adapted to be set up to resist opening of the damper except upon a full spout, a draft regulator comprising a cylinder, a piston therein coupled to said damper and movable conjointly therewith, said pistons having ports there- 45 through, a disc valve of less diameter than said cylinder lying freely on top of said piston, spring means normally urging said disc valve against said ports, and means for regulating the load of said disc valve.

9. In combination with a closed spout normally containing granular material, a movable damper therein opened by the movement of the material through the spout, means tending to close said damper, adjusting means for the damper closing 55 means adapted to be regulated to maintain the damper closed except upon a substantially full spout, a draft regulator comprising a cylinder closed at both ends, a piston mounted for reciprocation in said cylinder, a piston rod coupled to said piston and having connection to said damper, said piston dividing the cylinder into upper and lower chambers, a by-pass connecting the upper and lower chambers, a valve in said by-pass, a second supplemental by-pass connect- 60 ing with the upper portion of the cylinder and with an intermediate point therein above the lower end of the cylinder, said piston having ports therethrough, and valve means for yieldably closing said ports when the piston travels upwardly 65 and opening the ports when the piston travels downwardly.

10. In combination with a spout, a movable damper therein opened by the movement of the material through the spout, means tending to 75

- close said damper, a regulator for said damper, and an independently-operable gate adjacent said damper for regulating generally the volume of flow in the spout.
- 5 11. In an apparatus for transferring granular material from a bin to a conveyor in a grain elevator, a closed spout through which the granular material is adapted to gravitationally flow from the bin to the conveyor, a damper in
10 said closed spout, means for movably mounting said damper in the spout, means for biasing said damper to a closed position, and regulating means acting conjointly with the damper closing means for retaining the damper substantially closed against a free-running grain and until the closed chute is substantially filled with the grain.
- 15 12. In an apparatus for transferring granular material from a bin to a conveyor in a grain ele-
- vator, a closed spout through which the granular material is adapted to gravitationally flow from the bin to the conveyor, a damper in said closed spout, means for movably mounting said damper in the spout, means for biasing said damper to a closed position, regulating means acting conjointly with the damper closing means for retaining the damper substantially closed against a free-running grain and until the closed chute is substantially filled with the grain, said regulating means including means to resist the initial opening action of the damper to a higher degree than the final opening of the damper and also including means for permitting of a more rapid closing of the damper than of the opening movement thereof whereby to promptly shut off the flow of free-running grain when the closed spout is not filled throughout its diameter.

JAMES R. O'ROURKE.
